The ornamental design for a microbiologically interactive growth platform, as shown and described.

DESCRIPTION

FIG. 1 is a perspective view of a microbiologically interactive growth platform showing my new design:

FIG. 2 is a top plan view thereof;

FIG. 3 is bottom plan view thereof;

FIG. 4 is a front elevational view thereof;

FIG. 5 is a right-side elevational view thereof;

FIG. 6 is a rear elevational view thereof; and,

FIG. 7 is left-side elevational view thereof.

The dashed lines are included for illustrative purposes only and form no part of the claimed design.
